UNITED STATES PATENT OFFICE.

WILLIAM FAETHE, OF RAVEN ROCK, NEW JERSEY.

SANITARY CHICKEN ROOST.

Application filed November 19, 1923. Serial No. 675,521.

To all whom it may concern:

Be it known that WILLIAM FAETHE, a citizen of the United States, residing at Raven Rock, in the county of Hunterdon and State 5 of New Jersey, has invented certain new and useful Improvements in Sanitary Chicken Roosts, of which the following is a specification.

The invention relates to improvements in 10 roosts for chickens and other fowls, and the primary object is to provide an individual sanitary roost upon which the fowls must perch singly, thereby avoiding the congestion frequently experienced in the use of the 15 common forms of roosts.

Another object of the invention is to provide a sanitary roost so constructed that the droppings accumulated thereon may be quickly and easily removed.

20 A further object is to provide a portable vermin-proof chicken roost, which may be quickly set up in any desired place, including an adjustable extension perch ring and supporting legs and dropping tray, all being devoid of any crevices which might form 25 nesting places for vermin.

Other advantages may become apparent as the following description and claims are in part described and in part understood.

30 In the drawings—

Figure 1 is a side elevation of the complete roost;

Figure 2 is a plan view of a tray supporting member;

35 Figure 3 is a cross sectional view on line A—A in the direction of arrows;

Figure 4 is a fragmentary cross sectional view on the line B—B;

40 Figure 5 is a plan view of the complete roost.

Referring now more particularly to the drawing, 1 indicates the upright tubular legs, preferably composed of ordinary wrought iron pipe, which are formed outwardly at the lower extremity in the manner 45 designated. At the upper extremity each of the legs 1 is split at 5 downwardly in a vertical line, sufficiently to allow for a binding action on anything sliding within when the split portion 5 of the leg 1 is clamped together. Sliding within the split upper extremities of the legs 1 are a corresponding 50 number of smaller pipes 2 arranged in telescopic arrangement. These pipes 2 are

55 formed in the manner of brackets 2' at their upper extremities, upon which the annular

perch member 3 is mounted. The perch member 3 is composed preferably of wood or similar non-conductor of heat, thereby preventing any undue chilling of the fowls' 60 feet. The annular perch member 3 may be secured to the bracket portion 2' of the pipes 2 by means of ordinary wood screws. To hold the slideable portion of the sanitary roost in fixed relation with reference to the 65 stationary legs 1, collars 6 are provided, adapted to slide over the outside of the legs 1 and are disposed near the upper extremities thereof. These collars 6 are provided with threaded holes adapted to receive the set 70 screw 9 by means of which a clamping action may be effected when said screw 9 is turned against the split portion 5 of the legs 1. A dropping tray 4 is held at the lower extremity within the circumference of the three 75 outwardly extending legs. The tray 4 is composed of a flat piece of sheet metal having the edge thereof curled and having along the outer periphery projecting plates 7 and 8 respectively of the same number, and 80 positioned in a manner identical to the legs 1. The plate 7 is flat, while the plate 8 is formed in the manner of a bracket, and both are, however, riveted to the under side of the tray. Said projecting plates 7 and 8 re- 85 spectively have an eye part 10 through which the downwardly extending portion of the leg 1 is adapted to pass. The tray 4 is held in position by pins 11, which are passed through convenient holes in the legs 1. Thus 90 it will be seen that a positive method for holding the tray in position is provided, likewise, the removal of the tray may be thereby easily accomplished.

The operation of my device is as follows: 95 Since the device is comparatively light and sturdy, it may be quickly set up in the coops and the perch ring 3 may then be adjusted high or low at the will of the operator. After the fowls have roosted upon this device, 100 and droppings have accumulated, a small hoe may be used to scrape the dropping tray clean, or the pins 11 may be removed, thereby releasing the dropping tray free from the legs 1, whereupon the tray 4 may be very 105 easily cleaned.

While I have herein described a certain specific manner and method of constructing and assembling the elements of my invention, it is understood that I may vary from 110 the same in minor details, not departing from the spirit of my invention, so as best

to construct a practical device for the purpose intended, as defined in the appended claims.

I claim:

- 5 1. A portable sanitary roost of the class described, comprising upright, fixed tubular frame members; a corresponding set of tubular frame members adapted for vertical telescopic relation to the main upright members; an annular perch member mounted upon the slideable tubular members; means for holding the perch member in a variation of positions; a dropping tray detachably held at the lower extremities of the upright
- 10 fixed members; and means for releasing the tray from the stand for cleaning purposes.
- 15 2. A sanitary poultry roost of the class

described, comprising upright, fixed tubular frame members, supporting at their lower extremities a suitable dropping tray; 20 means provided for detachably holding the dropping tray in position; another set of movable frame members adapted for vertical, slideable, telescopic movement relative to the fixed members; an annular perch member mounted on the upper extremity of the movable members; and a clamping collar provided to lock the perch member in any predetermined position.

In testimony whereof I affix my signature.

WILLIAM FAETHE.
